UNITED STATES PATENT OFFICE.

LLOYD GROFF COPEMAN, OF FLINT, MICHIGAN, ASSIGNOR TO COPEMAN ELECTRIC STOVE COMPANY, OF FLINT, MICHIGAN, A CORPORATION OF MICHIGAN.

ELECTRIC STOVE.

1,141,175

Specification of Letters Patent.

Patented June 1, 1915.

Application filed April 18, 1913. Serial No. 762,061.

To all whom it may concern:

Be it known that I, LLOYD GROFF COPEMAN, a citizen of the United States of America, residing at Flint, in the county of Genesee and State of Michigan, have invented certain new and useful Improvements in Electric Stoves, of which the following is a specification, reference being had therein to the accompanying drawings.

10 My invention relates to an electric stove and more particularly to a stove formed of a hot plate and an oven which is detachable therefrom so as to permit the hot plate to be employed independently of the oven.

15 The invention resides in the novel construction, arrangement and combination of parts as will more fully hereinafter appear.

In the drawings,—Figure 1 is a central, vertical section through a device embodying my invention; Fig. 2 is a perspective view of the hot plate with the shield removed, looking at the bottom thereof; Fig. 3 is a similar view of the shield; and Fig. 4 is a perspective view of the bearing member; Fig. 5 is a fragmentary, perspective view of the bottom side of the oven.

In the drawing, A designates the hot plate and B the oven. The former has a base C supported by suitable legs D and this base has the central portion thereof provided with an aperture E within which is arranged the electrical heating element F. The latter is supported by means of a plurality of arms G cast integral with the base and extending into the opening E. These arms are so shaped as to position the element F slightly above the plane of the top face of the base. Secured to the base—preferably at the front side thereof—is a bracket H that carries a switch I for the electrical connector, the switch and the connector being connected to the heating element in any desirable manner.

In order to protect the support upon which the base rests, from the heat of the element F, a shield J is provided which not only is made detachable but also is preferably so shaped as to serve the additional function of a drip pan. The member J is provided with a downwardly-extending flange K which has outwardly-extending lugs L that are adapted to engage and rest upon a laterally-extending flange M of a bearing member N, while at the opposite

side of the shield J is a flange O provided with indentations P for receiving projections Q on spring lugs R of a second bearing member S, the latter being arranged upon the base at the side opposite from that of the bearing member N.

Preferably the member N is secured to the base by means of screws T that serve to attach the bracket to the base. Thus the last-mentioned bearing member has an upwardly projecting lip U arranged intermediate the bracket and the skirting V of the base C, and is apertured to permit the securing screws T to pass therethrough.

W is an enlarged lateral extension of the bearing member N which projects inwardly adjacent the switch and serves as a shield for the insulated wires X between the switch and the terminal block Y of the electrical element, thereby maintaining the wires out of contact with the heating surface of the element. The shield J has the flange K thereof cut away at a to permit the wires and the extension W to pass therethrough.

The oven B is provided with an aperture A' in the bottom thereof, which aperture is preferably of configuration complementary to the configuration of the element F but is slightly larger than the element so that the latter will not come in contact with the walls of the oven. So also the element F does not engage the walls of the base C. In order to properly position the oven so that the walls B' of the aperture A' will not engage the heating element, positioning members C' are arranged to engage the several sides or skirting of the base. These positioning members are preferably in the form of angle strips having one portion as D' fixed to the bottom face of the oven and having the downwardly-projecting portion E' suitably shaped to fit the skirting. The strip at the front edge of the oven has the downwardly-extending flange E' thereof recessed at F' to receive a portion of the switch I.

As before stated, the oven bottom is provided with an aperture A' that extends therethrough. Therefore, in order to obtain a better distribution of the heat within the oven, a deflector G' is arranged within the oven directly above the opening A'. This shield is preferably carried by the lower rack H' of the oven, which has down-

wardly-extending projections I' which serve to maintain the shield a distance above the oven bottom.

When it is desired to use the oven, the parts are assembled as shown in Fig. 1, the member C' serving to position the oven so that the walls B' of the opening A' are out of contact with the heating element. When the hot plate only is to be employed, it is merely necessary to lift the oven from the hot plate and the receptacle containing the food or the like to be cooked or heated, may be placed directly upon the top face of the element F.

15. What I claim as my invention is:—

1. In an electrical heating element, the combination with a base provided with an aperture, an electrical heating element arranged in said aperture and carried by the base, and a combined flanged drip-pan and shield detachably connected to the base and arranged beneath said heating element.

2. An electrical hot plate, comprising a base having an aperture therein, an electrical heating element arranged in the aperture, bearings upon the underside of the base, and a combined shield and drip-pan detachably carried by said bearings.

3. An electrical hot plate, comprising a base having an aperture therein, an electrical heating element arranged in said aperture and carried by the base, a switch mounted upon the base, electrical connections between the switch and the hot plate, and a shield intermediate the switch and hot plate for said electrical connectors.

4. The combination with an electrical hot plate including an electrical heating element, of an oven supported thereon and provided with an apertured portion arranged over the heating element, a rack positioned in the oven and spaced from the bottom thereof, and a deflector carried by the rack and extending across said opening.

45. 5. The combination with a hot-plate, in-

cluding a base and an electrical heating element supported upon said base and projecting above the plane of the top face thereof, of a closed oven detachably engaging said base having the bottom thereof provided with an aperture of a size to receive said hot-plate, and members projecting from the bottom face of the oven and engaging the skirting of the pan for positioning the oven upon the base to maintain the walls of the apertured portion out of contact with the hot-plate.

6. In an electrical heating element, the combination with a base having an aperture therein, of an electrical heating element arranged in said aperture and carried by arms attached to said base, electrical connections to said heating element, a combined drip-pan and shield positioned beneath the heating element, a supporting member therefor, said member holding said electrical connections from contact with the heating surface of said electrical element.

7. The combination with a hot plate, including a base having a centrally located opening, arms attached to said base projecting up into said opening and supporting legs attached to said base, and an electrical heating element supported upon said arms and projecting above the plane of the top face thereof, of an oven detachably engaging said base having the bottom thereof provided with an aperture of a size to receive said heating element, and channel irons attached to said oven for positioning said oven upon the base to maintain the walls of the apertured portion of the bottom out of contact with said heating element.

In testimony whereof I affix my signature in presence of two witnesses:

LLOYD GROFF COPEMAN.

Witnesses:

ROY W. SCHUMACHER,

FRANK D. MONTAGUE.
